UNITED STATES PATENT OFFICE.

CONRAD HENNECK, OF FRISCO, COLORADO.

CARBIDE-LAMP HOLDER.

Application filed August 6, 1926, Serial No. 127,648. Renewed September 7, 1928.

The object of this invention is the provision of a stand or support for calcium carbide lamps employed by miners in mines that shall be characterized by simplicity in construction and reliability in practical use.

To the attainment of the foregoing the invention consists in the improvement as hereinafter described and definitely claimed.

In the drawings:

- 10 Figure 1 is a perspective view of the improvement.
Figure 2 is a side elevation thereof showing the same supporting a lamp thereon.
In mines it is frequently necessary to employ a special tool for arranging a hitch in the solid walls upon which to support lamps. Such supports are insecure and the least jolt causes the dislodgement of the same, with the result that much money is lost to the mine 20 owners by lost lamps and the waste of time in finding supports for such lamps. This is also true when lamps are hung in loose ground as the removal of layers thereof interferes with hitch or support. Therefore I have produced an extremely simple but novel holder or support for lamps in mines which can be arranged at any desired angles so that the rays of light will be properly directed and which will effectively support the lamps 30 thereon so that the same cannot be dislodged except by hand. Also with my improvement the lamp may be suspended at varying desired elevations.

In carrying out my invention I make use of 35 two preferably metal plates 1—1. Each plate is offset at one of its ends to provide a foot 2. The spaced plates 1, at desired intervals, are connected by transverse strips 3, and each of

these strips has a central opening 4 therethrough. The opening 4 is designed to receive 40 therethrough the hook 5 of a lamp 6 and the beaded lower edge of the font of the lamp will have its rear portion received between and disposed in contact with the confronting 45 edges of the spaced strips so that the same is effectively supported in a manner to prevent the swinging of the lamp in any direction. The support may be arranged at any desired angle in the mine, and the lamp may be attached to any of the transverse strips 3. 50

It is, of course, to be understood that the carbide lamp holder is not to be restricted to use in mines as the same may be successfully employed in any place where carbide lamps are in use. 55

The simplicity and advantages of my improvement will, it is thought, be apparent to those skilled in the art to which the invention relates.

Having described the invention, I claim: 60
A miner's lamp support which is designed to rest at an angle between a side wall and the floor of a mine, comprising a pair of spaced parallel members having offset ends providing feet, spaced transverse strips connecting the members and each of said strips having a central opening therethrough for the reception of the hook of a lamp, said spaced members being adapted to receive between and have their confronting edges contact with the rear portions of the font of the lamp to prevent swinging of the lamp when arranged upon the support. 65
70

In testimony whereof I affix my signature.

CONRAD HENNECK.
